United States Patent Office

Des. 232,604
Patented Sept. 3, 1974

232,604

SKIRT

Gloria C. Kadison, P.O. Box 626,
Thousand Oaks, Calif. 91360

Filed Oct. 19, 1972, Ser. No. 298,849

Term of patent 14 years

Int. Cl. D2—02

U.S. Cl. D2—223

Fig. 1

Fig. 3

Fig. 2

Fig. 5

Fig. 4

Fig. 6

FIG. 1 is a front perspective view of a skirt showing my new design in an unfastened position, the bottom corner of the skirt portion that overlaps being turned up;

FIG. 2 is a front perspective view thereof in a fastened position;

FIG. 3 is a top plan view thereof;

FIG. 4 is a front elevational view;

FIG. 5 is a side elevational view;

FIG. 6 is an elevational view of the other side.

I claim:

The ornamental design for a skirt, substantially as shown and described.
